UNITED STATES PATENT OFFICE.

FRIEDRICH HERMANN THIER, OF KOENIGSTEIN, GERMANY.

HAND-REST.

SPECIFICATION forming part of Letters Patent No. 655,284, dated August 7, 1900.

Application filed October 13, 1899. Serial No. 733,516. (No model.)

To all whom it may concern:

Be it known that I, FRIEDRICH HERMANN THIER, a subject of the King of Saxony, residing at Koenigstein, Saxony, German Empire, have invented certain new and useful Improvements in or Relating to Hand-Rests, (for which I have made application for patent in Germany, design Patent No. 117,946, dated June 3, 1899; in Great Britain, No. 11,986, dated June 8, 1899; in Switzerland, filed June 12, 1899, and in Austria, filed June 12, 1899,) of which the following is a specification.

The object of the present invention is a hand-rest for use when writing in thick books or the like.

The hand-rest consists of two leaves, plates, boards, or frames *b b*, hinged together at *c*, the plates being made of wood, metal, or the like, the upper one being provided with a slot *c* for the purpose of guiding a pin *d*, projecting from a wedge *e*, arranged between the two plates *b b*. The nearer the said wedge *e* is placed to the hinges connecting the two plates *b b* the greater will be the distance between the outer edges of the two plates, the upper one of which will occupy an inclined position. By resting the hand on the upper plate the latter will secure the weight *e* in position. A nut or knob *f* is preferably arranged in the top of the pin *d* to aid in moving and securing the wedge in position.

In order to be able to fix the hand-rest to the book, &c., when there is no room on the table for the placing of the lower plate, the

latter may be provided with a thin plate *g*, 35 of metal or the like, revolubly pivoted on a fixed point of the said plate, the thin plate being placed between the leaves of the books or between the book and the top of the table in order to afford a support to the hand-rest. 40

What I claim as my invention, and desire to secure by Letters Patent, is—

1. A hand-rest comprising two leaves hinged together at their edges, a wedge adjustably arranged between the two leaves and a thin 45 plate pivoted on the under side of one of the plates substantially as described.

2. A hand-rest comprising two leaves hinged together at their edges, a slot in one of the leaves a wedge provided with a pin projecting through said slot, and means for adjusting and securing said pin in the slot substantially as described. 50

3. A hand-rest comprising two leaves hinged together at their edges, a slot in one of the 55 leaves, a wedge provided with a pin projecting through said slot and means for adjusting and securing said pin in the slot and a thin plate pivoted on the under side of the plate substantially as described. 60

In testimony whereof I have signed my name to this specification in the presence of two subscribing witnesses.

FRIEDRICH HERMANN THIER.
